UNITED STATES PATENT OFFICE.

HAROLD W. EVANS, OF WASHINGTON, DISTRICT OF COLUMBIA.

PUPPET-VALVE.

1,358,429.

Specification of Letters Patent. Patented Nov. 9, 1920.

Application filed May 19, 1919. Serial No. 298,301.

(FILED UNDER THE ACT OF MARCH 3, 1883, 22 STAT. L., 625.)

To all whom it may concern:

Be it known that I, HAROLD W. EVANS, a citizen of the United States, stationed at Washington, D. C., have invented an Improvement in Puppet-Valves, of which the following is a specification.

The invention described herein may be used by the Government, or any of its officers or employees in prosecution of work for the Government, or by any other person in the United States, without payment of any royalty thereon.

This invention relates to puppet-valves for internal combustion engines, and one of its objects is to design a valve having a spindle or stem operable directly from the cam-shaft so as to dispense with push rods and other intermediate parts incidental to assemblies of this type.

Another object of this invention is to provide a puppet-valve having means for modifying the length of its stem to enable rapid and convenient adjustment.

Another object is to provide a valve assembly having means for normally locking its adjustable parts to prevent disarrangement subsequent to adjustment.

With these and other objects in view my invention consists in certain novel details of construction, combination and arrangement of parts to be more particularly set forth and claimed. Referring more particularly to the accompanying drawing in which corresponding parts are indicated by similar reference characters:

Figure 1 is a transverse vertical section partly in elevation, taken along the axis of the valve;

Fig. 2 is a horizontal section on the line 2—2 of Fig. 1;

Fig. 3 is a similar view on the line 3—3 of Fig. 1.

Briefly stated, this invention comprises a valve having a hollow stem, a valve stem guide, inner and outer compression springs, a tappet provided with an externally threaded spindle telescopically engaging a valve stem, a spring retainer and adjusting collar having an outwardly inclined flange adapted to seat in a similarly shaped retaining flange formed on the tappet and means affording an interlocking engagement between the spring retainer and adjusting collar and valve spindle.

In the illustrated embodiment character-

izing this invention there is shown a fragment of a standard internal combustion motor *a* having a valve seat *b*, seating a valve *1*, the spindle *2* of which projects through a guide *3*. The guide *3* is separate from the head casting and removable therefrom; midway its length it is provided with a shoulder *3^a*.

The spindle *2* is hollowed throughout the greater portion of its length as at *4*, the hollow portion being provided with tapped threads *5* to engage threads *6* formed on spindle *7* of the tappet *8*, when the former is telescopically positioned in valve spindle *2*. Tappet *8* is formed with a flange *9*, the inner surface of which is downwardly and outwardly inclined as at *10* to provide a seat for the similarly shaped outer surface *11* of spring retainer and adjusting collar *12*. Inner and outer compression springs *13* and *14* encircling guide and spindle *2* and *3*, by their pressure on collar *12* cause the latter to be firmly wedged in its seat thus producing a frictional interlock between these parts. The inner compression spring *13* encircling the guide and spindle bears at its lower end against the shoulder *3^a* on the valve stem guide and at its upper end bears against the collar *12*.

The outer compression spring *14*, as explained, bears against a part of the valve seat and forces the collar into engagement with the tappet, while the inner compression spring *13*, bearing at its upper end against the collar, serves in part the same purpose, but in addition thereto, by its pressure on the shoulder on the removable valve stem guide it serves a secondary purpose of maintaining the valve stem guide in position.

Tool openings *15* and *16* in tappet and adjusting collar permit their actuation when a clearance adjustment is being made. Collar *12* is fixedly secured to valve stem *2* adjacent its lower end by means of tongues *17* fitted into slots *18* formed in said spindle.

The cam *19* on the cam-shaft *20* engages tappet *8* and operates the valve *1* in the usual manner.

In order to adjust this form of valve assembly to obtain the proper clearance, compression springs *13* and *14* are compressed whereupon collar *12* is disengaged from its seat in the tappet. After release of collar *12*, the latter is retained in a fixed position by a tool or otherwise and tappet *8*

rotated to withdraw or cause the spindle 7 of the tappet to pass farther into the spindle 2 of the valve dependent upon the exigency of the situation. The adjustment being 5 made, compression springs 13 and 14 are released to return collar 12 to its initial position in the tappet so that tappet 8 and collar 12 function as a unitary structure.

Interlocking the tappet and adjusting 10 collar in this manner manifestly prevents any disarrangement of the parts after the clearance adjustment has been made.

By the preceding construction the efficiency 15 of the motor is materially increased since push rods and other intermediate parts tending to increase the inertia of the valves are entirely dispensed with. Moreover, employing a valve of this kind tends to reduce not only the cost of production but of replacements 20 as well.

Although in the foregoing certain elements have been enumerated as best adapted to perform the functions allotted to them, nevertheless it is understood that various 25 minor changes may be resorted to within the scope of the appended claims without departing from or sacrificing, any of the principles of this invention.

Having thus described the invention what 30 I claim as new and desire to secure by Letters Patent is:

1. A puppet valve comprising a stem formed of telescopically engaged sections having co-acting means for effecting their longitudinal adjustment, a valve on one section, a tappet on the other section, said tappet provided with a seat formed with a flaring

inner surface, an adjusting collar within said seat conforming to the shape thereof, a separate removable valve stem guide provided 40 with a shoulder, a spring interposed between the shoulder on the valve stem guide and the collar, and means for normally maintaining said tappet and valve in locked relation.

2. A puppet-valve assembly comprising inner and outer telescopically engaged sections having co-acting means for effecting their longitudinal adjustment, a valve on the outer section, a tappet on the other, the latter being formed with a seat, said seat being provided with a flange, said flange having a downwardly and outwardly inclined inner surface, an adjusting collar located within said seat and conforming to 55 the shape of same and connected with the outer section of the stem, and a compression spring coöperating with said collar to effect its securing within said seat.

3. A puppet-valve assembly comprising 60 inner and outer telescopically engaged sections having coacting means to effect their longitudinal adjustment, a valve on said outer section, a tappet on the other having a seat formed with a flaring inner surface, 65 an adjusting collar within said seat, and having a tapered exterior surface to produce a wedge like action between collar and tappet and a compression spring securing the collar within its seat.

HAROLD W. EVANS.
